(57) **CLAIM**

The ornamental design for a magazine, as shown and described.

DESCRIPTION

FIG. 1 is right side elevation view of a magazine showing our new design;

FIG. 2 is a left side elevation view of the magazine of FIG. 1; FIG. 3 is a rear elevation view of the magazine of FIG. 1; FIG. 4 is a front elevation view of the magazine of FIG. 1; FIG. 5 is a top view of the magazine of FIG. 1; FIG. 6 is a bottom view of the magazine of FIG. 1; FIG. 7 is a left, top, front perspective view of the magazine of FIG. 1; and,

FIG. 8 is a left, top, rear perspective view of the magazine of FIG. 1.

The broken lines showing portions of the design in all figures are included for the purpose of illustrating environment and unclaimed features and forms no part of the claimed design.

1 Claim, 8 Drawing Sheets(56)
